Bed Boat or Life Preserver

No 12,450.

Patented Feb 27, 1855.

UNITED STATES PATENT OFFICE.

JOSEPH STEVENSON, OF PHILADELPHIA, PENNSYLVANIA.

BED-BOAT OR LIFE-PRESERVER.

Specification of Letters Patent No. 12,450, dated February 27, 1855.

To all whom it may concern:

Be it known that I, J. STEVENSON, of the city of Philadelphia, in the county of Philadelphia and State of Pennsylvania, have invented a new and Improved Bed-Boat or Life-Preserver for the Safety of Persons Traveling by Water, the whole being so constructed that in case of accident to the vessel, it can in a few minutes be converted 10 into a life-boat, or a number of them being lashed together will form a substantial raft, upon which the passengers and crew may trust themselves in case of emergency.

The following is a full, clear and exact 15 description of the same; reference being had to the annexed drawings, making a part of this specification in which—

Figure 1 is a drawing of the bed boat, and mattress, the whole being arranged for 20 a single berth; when required for a double berth, the back is thrown down the mattress of course covering the whole; Fig. 2, is a top plan of a portion of the boat; one end only is shown in the drawing, the other end being precisely similar is omitted. This part 25 forms when in use on shipboard a framing or bottom for the bedding to lie upon; when brought into use as a boat this will form the inside; this part is also covered with india rubber cloth in order to render it water- 30 proof. Fig. 3 is a reversed or bottom plan of the same; this view shows the under part of the framing when in the berth or when in use as a boat, what constitutes the outside. 35 Fig. 4 is a perspective view of the machine converted into a boat. Fig. 5 is a view of a portion of one side, or rather one-half, of the framing, being partly in section, for the purpose of showing the manner of converting 40 the same. Fig. 6 is a transverse view of the same. Fig. 7 is a diagram showing the manner of arranging the boats, for the purpose of forming a raft.

The same letters refer to like parts; letter 45 *a* being the mattress or bed; *b* the framework which forms the sides of the boat; *c* the part which forms the bulkhead or ends of the boat when in use on shipboard. These parts fold underneath, as shown in Fig. 1, 50 the bottom of the berth being cut out to admit their passing through.

d shows the air tube with the stop-cock *e* attached to it; *f*, the india rubber cloth apron or flap intended when the bed is converted 55 into a boat to keep out the water, they being drawn up and securely fastened

to the knobs *g*; when in use as a bed stand the aprons may be spread out flat, as shown in Fig. 2, or formed into a roll under the ends of the mattress; *g*, knobs to which the different lashings are secured; *h*, the cords; in Figs. 2 and 3 they are shown drawn back or loosened in order that the ends marked *c* may be turned underneath as shown in Fig. 1; they should be of sufficient length to remain in the eyelets, in order that no unnecessary delay may be caused when occasions arise to use the machine as a boat.

i, is a hollow belt of india rubber cloth covering, the joint formed by the junction of the two sides; hooks or their equivalents being used for securing the bed or mattress to the frame, the mattress having corresponding loops; the belt or tube is also made sufficiently long for one end to be passed over the bow of the boat as shown in Fig. 4; it is intended that this tube should be used as a pump to keep the boat dry, a valve being fixed at the other end, which will admit the water into the tube from which it may be forced by a pressure of the foot; *k* copper rivets or nails which fasten the canvas covering to the frame work; *l*, holes in the covering, admitting the water into the lower part of the framing to serve as ballast, to keep the boat in an upright position.

m and *n*, are the vertical and horizontal framing, showing the manner of putting them together; *o*, a layer of cork, running the whole length of the framing, and extending downward to a distance occupying two spaces between the horizontal fastenings. *p*, is also a layer of cork filling the interstices, between the vertical pieces of frame work running parallel with *e*, and of the same extent each way.

x, is the handles serving the purpose of row locks when used as a boat, and through which the lashings may be passed and secured when formed into a raft. The dotted lines in Fig. 3 show the framing of light wood which forms the bows or ends of the boat the inside space being filled in with cork. The two sides are joined or fastened together by strap hinges made of girth web. In order to construct the machine, we first make a strong framing of ratan, or any suitable material, as shown in Figs. 5 and 6, and of any required length and breadth; at the top bottom, and each end, a double thickness of ratan is used. The framework at each intersection being securely and firmly

fastened together by lashings of small cord the next process is to put the layers of cork in their proper places the outer layers being secured between the horizontal braces, and occupying two spaces between the vertical bracings extending each way the same distance as the other layer. The whole is then covered with strong heavy canvas which is secured at each intersection of the framing, 10 by copper rivets or nails. The canvas covering the air tube *d*, in order to retain it in its place and protect it from injury by chafing, &c.

A stop cock is attached to the tube; allowing the tube to be filled with air and preventing its escape when once filled. The framing of the ends are made to resemble somewhat the bows of a boat in shape are also covered in a similar manner with canvas, and hinged to the sides in any suitable manner. The two sides are joined or fastened together with girth web, forming a common strap hinge which enables the machine to lie flat or fold together the part 25 which forms the inside of the boat is lined with india rubber cloth making the boat waterproof. The tube of india rubber cloth is next placed over the joint, its use is to retain the bed or mattress in its place and 30 also to expel any water that may lash into the boat it can, however, be dispensed with without detriment to the successful working of the other parts of the apparatus. One-half of the bows, as shown in Fig. 3, is covered with canvas, said canvas being loose at the part containing the eyelets; a canvas flap of similar shape and construction is fastened to the opposite side of the boat; the cord for lashing and holding the parts together passes through these eyelets.

I do not confine myself to the precise arrangement as herein set forth nor the materials mentioned, as it may be necessary to modify the same to suit circumstances, as 45 the same may be done without affecting the principle or mode of action.

In case it should be necessary to convert the machine into a boat, all that you will have to do, will be to turn up the sides, put the bows in their places, draw the cords 50 tightly, and fasten them to the knobs; next draw the apron of india rubber cloth together, and secure the cords to the knobs. The boat is then ready for launching. Should it be preferred to construct a raft a 55 number of the boats may be lashed together (the diagram, Fig. 7, shows a very suitable arrangement). In order to render the raft stiff oars or any suitable light spars may be lashed transversely as shown in the diagram. 60 The mattress may be left in the boat, or not as the passenger chooses, being properly secured in its place by means of hooks and loops there is no danger of its shifting, and if more buoyancy is wanted when the boat 65 in the surf would chance to fill with water air tight pillows fastened to the bed in the position to sit on would give more buoyancy to the boat when filled with water.

Having thus fully described the nature of 70 my invention, I would state that I do not claim the material of which the boat is constructed, nor do I claim a flexible or fold up boat, as these are not new, but

What I do claim as new and desire to secure by Letters Patent is—

1. So hinging the bulkheads or bows to a flexible boat as that they may be turned down out of the way for stowage in the bunks or births of a vessel, and may be as 80 readily drawn up and laced so as to form a bow, substantially as described.

2. I also claim in combination with the hinged bulkheads or bows, the apron which is drawn up over the joint of the two bulkheads, for the purpose of preventing any water from entering the boat through said joints, in the manner described.

JOSEPH STEVENSON.
